WIDE BAND STUB LINE DEVICE

Hugh K. Clark, Waynesboro, Va., assignor to the
United States of America as represented by the
Secretary of War

Application February 18, 1946, Serial No. 648,545

5 Claims. (Cl. 178—44)

1

This invention relates generally to electrical circuits and more particularly to a means for injecting voltages of other than radio frequencies into a coaxial radio-frequency transmission line.

It is frequently desirable to utilize an R.-F. transmission line to carry, in addition to its normal radio-frequency signal, an additional direct current or a power-frequency current, for example, one of 60 cycles per second. These currents do not interfere in any way with the normal radio frequency current of the line; however, if certain precautions are not taken at the points of injection and removal of the current from the line, the standing wave ratio of the line may be greatly increased due to a mismatch of impedance at these points.

It is therefore an object of the present invention to provide a means for injecting into and removing from a coaxial radio-frequency transmission line a direct or power-frequency current. It is a further object to render this means physically small. It is still another object so to design this means that the standing wave ratio of the line remains low over a band of frequencies, and so that radio-frequency power losses from the line over this frequency band are not appreciable.

Other objects, features and advantages of this invention will suggest themselves to those skilled in the art and will become apparent from the following description of the invention taken in connection with the accompanying drawing which shows a circuit diagram for a device of the type contemplated by the invention.

In the drawing there is shown a radio-frequency coaxial transmission line consisting of an inner conductor 10 and an outer conductor 12. Points 14 and 16 on conductor 10 are the input and output points, respectively, for the direct or low-frequency voltage, while capacitors 18 and 20 are radio-frequency bypass capacitors inserted in the central conductor 10 to permit the flow of radio-frequency current while preventing the flow of low-frequency or direct current through R.-F. terminals 22 and 24. The injector unit itself includes a first section of coaxial line consisting of an outer conductor 26 and a coiled inner conductor 28, the latter being connected to conductor 10 at point 14. A second section of coaxial line consisting of an outer conductor 30 and an inner conductor 32 is connected in series with the first section, the ratio of the total effective lengths of the first and second sections being 3:1 or less. At the junction of the two sections, there is placed a loading unit consisting of four equal resistors

2

34, each in series with a capacitor 36, connected between the inner and outer conductors of the line sections. Capacitors 36 are R.-F. bypass capacitors; that is, they offer low impedance to radio frequencies but high impedance to D.-C. or low frequencies. The values of the resistors 34 are made such that their parallel resistance is approximately equal to the magnitude of the characteristic impedance of the line sections, 10 which is almost entirely resistive. An R.-F. bypass or shorting capacitor 38 is connected between the inner and outer conductors of the second line section at a point near the end thereof. The D.-C. or low-frequency input is applied to terminals 40, one connected to the central conductor of the line section and the other being grounded and connected to the outer conductor thereof. An ejector unit 42 identical with the injector unit just described is connected between point 16 on 20 the inner conductor of the transmission line and the output terminals 44 through which the direct or low-frequency voltage is removed.

Since capacitor 38 presents a negligible impedance to radio frequency, the injector line section 25 without the loading resistors would appear electrically as a short-circuited stub in parallel with the main transmission line. At the frequency at which its total electrical length is one-fourth wavelength, the stub would present a very high 30 impedance and have little effect on the main transmission line; however, at other frequencies its impedance is less, and it serves to increase the standing wave ratio on the line. At the frequency at which the total electrical length of the 35 stub is one-half wavelength, it would offer a very low impedance, short-circuiting the transmission line and rendering its operation impossible. The decrease of impedance is such that if the main transmission line is terminated in its characteristic 40 impedance and has, for example, a characteristic impedance of 50 ohms, while that of the stub is 180 ohms, the standing wave ratio on the line is less than or equal to 2:1 over a frequency band whose upper and lower limits are in a ratio 45 of 7.4:1.

In order to increase the useable frequency band and to avoid the short circuiting effect caused when the stub is one-half wavelength, the stub is loaded with its characteristic impedance at a 50 point which is at least one-fourth of the distance from the shorted end of the stub, to the point of connection to the main line. This resistance has relatively little effect at lower frequencies, being in parallel with an inductance whose impedance 55 is much smaller, but at the frequency at which

the total length of the stub is one-half wavelength, because of this loading, the impedance presented by the stub will have an appreciable value.

It has been determined experimentally that if the loading is too close to the shorted end of the stub, at the frequencies at which the stub length is one-half wavelength the stub presents an extremely low impedance. Moving the load away from the shorted end increases the impedance presented. This impedance, as stated above, becomes appreciable when the loading occurs at a point which is at least one-quarter of the total stub length away from the shorted end. However, increasing this loading distance from the shorted end also has the effect of lowering the highest frequency at which the stub can be used, which occurs when the distance between the loading point and the short circuited end is one-half wavelength.

As an example, assuming the resistive load is one-fourth of the distance from the end of the stub and that the values of characteristic resistance are as given above, when the stub is one-half wavelength long the impedance of the stub would be 72-736 ohms at the injection point. Under these conditions a standing wave ratio of 1.6 is produced on the transmission line, and about 60 per cent of the radio-frequency power sent down the line is dissipated in the load. The remainder is either reflected or dissipated in the stub load resistance. Since the stub with resistor load is effective not only at the frequency at which it is one-half wavelength long but also at higher and lower frequencies, the bandwidth of the device is improved considerably by resistive loading. The upper limit of the frequency band is in this case determined by the frequency at which the distance from the load resistors to the shorting capacitor is one-half wavelength. The purpose of the coiled inner conductor is to decrease the size of the stub injector unit to about one-sixth the length of a unit in which the inner conductor is straight. The purpose of using four load resistors is to minimize the effective inductance of the resistive load. Capacitors 36 act as short circuits for radio frequency while preventing the direct or low-frequency voltage from being short-circuited to ground by the rather low value resistors 34. Obviously unit 42, which is identical with the unit whose operation has just been described, may be used to remove the direct or power-frequency current from the transmission line.

While there has been described what is at present considered to be the preferred embodiment of this invention, it will be obvious to those skilled in the art that various changes and modifications may be made therein without departing from the scope of the invention.

The invention claimed is:

1. In combination, a coaxial radio-frequency transmission line having an outer conductor, an inner conductor and input and output terminals; first and second coaxial line sections connected substantially in parallel with said transmission line at two given points thereof, each of said line sections having a coiled inner conductor; two radio-frequency bypass capacitors, one of said capacitors connected between the inner and outer conductors of each of said line sections at the terminations thereof; a plurality of resistors connected to the inner conductor of each of said line sections at a point at least one-quarter of the distance from the radio frequency shorted end there-

of to the point of connection thereof to said transmission line, the distance of said point from said radio frequency shorted end also being less than an integral multiple of one half wavelength of the radio frequencies being transmitted by said transmission line, the parallel resistance of said resistors being approximately equal to the characteristic resistance of the line section in which they are connected; a plurality of radio-frequency bypass capacitors each one connected respectively between each one of said plurality of resistors and the outer conductors of said line sections; two radio-frequency bypass capacitors inserted in the inner conductor of said transmission line between said input and output terminals respectively and the remainder of said inner conductor; and a plurality of means adapted to apply direct and low-frequency voltages between the inner and outer conductors of said first line section at the termination thereof, a plurality of means adapted to remove direct and low frequency output voltages from between the inner and outer conductors of said second line section at the termination thereof.

2. In combination, a coaxial radio-frequency transmission line having an outer conductor, an inner conductor and input and output terminals, a plurality of pairs of coaxial line sections connected substantially in parallel with said transmission line, each of said pairs including a first section and a second section, two radio-frequency bypass capacitors inserted in the inner conductor of said transmission line between said input and output terminals respectively and the remainder of said inner conductor, a plurality of radio-frequency bypass capacitors connected respectively between the inner and outer conductors of each of said line sections at the terminations thereof, resistive load means electrically connected to each of said line sections at a point at least one-quarter of the distance from the termination thereof to the connection thereof to said transmission line, the distance of said point from the said termination also being less than an integral multiple of one half wave length of the radio frequencies being transmitted, and a plurality of means adapted to apply direct and low-frequency voltages between the inner and outer conductors of said first line sections at the terminations thereof, a plurality of means to remove direct and low frequency output voltages between the inner and outer conductors of said second line sections.

3. A wide band stub line device for a radio frequency coaxial transmission line, comprising a coaxial conductor having an outer conductor and a coiled inner conductor, a first end of said coaxial conductor being adapted to electrically couple to said transmission line, a radio-frequency bypass capacitor connected at a second end of said coaxial conductor between its outer and inner conductors, means at said second end to receive direct and low frequency voltages, resistive load means having a resistance substantially equal to the coaxial conductor characteristic resistance, said means being electrically connected between said coiled inner conductor and said outer conductor at a point at least one quarter of the total length of the coaxial conductor from its second end, the distance from said point to the second end of said coaxial conductor being less than an integral multiple of one half wave length of the radio frequencies with which the device is to be used.

4. A wide band stub line device as defined in claim 3, wherein said resistive load means com-

prises at least one resistor connected at one end to the said point on the coiled inner conductor and at least one radio frequency bypass capacitor connected between the other end of said resistor and the outer conductor.

5. A wide band stub line device as defined in claim 3, wherein said second end having the radio frequency bypass capacitor is terminated in means to remove direct and low frequency voltages.
